UNITED STATES PATENT OFFICE.

FRANK E. BOGA, OF MONTICELLO, INDIANA.

DISPLAY RACK.

Application filed March 26, 1923. Serial No. 627,823.

To all whom it may concern:

Be it known that I, FRANK E. BOGA, a citizen of the United States, residing at Monticello, in the county of White and State of Indiana, have invented certain new and useful Improvements in Display Racks, of which the following is a specification.

This invention relates to new and useful improvements in display racks and more

10 particularly for the displaying of various kinds of merchandise, the main object of the present invention being the provision of a display rack wherein the construction and arrangement of the several parts are particularly adapted for supporting caddies which are used for shipping tea and other merchandise of this character.

Another object of the invention is the provision of a display rack for displaying 20 various kinds of merchandise, wherein the merchandise will be mounted upon the rack in such manner as to present a uniform appearance when viewed from the front of the rack.

25 A further object of the invention is the provision of a display rack of this character provided with adjustable features, whereby the device will accommodate articles of merchandise of various size and shape, and permit of the arrangement of these articles in such a manner as to present a comparatively uniform appearance.

30 A further object of the invention is the provision of a display rack, whereby the several parts of the rack may be quickly and easily assembled or disassembled and when disassembled occupy a minimum of space for storing or shipping.

35 A further object of the invention is the provision of a display rack, wherein the several parts of the rack are constructed of suitable material to withstand hard usage and to prolong the wearing quality, and at the same time these parts being rigidly connected to prevent the same from becoming loosened or disassembled when in use.

40 With the above and other objects in view, the invention consists in the novel construction, the combination and arrangement of parts as pointed out in the appended claims and shown in the accompanying drawings.

45 Figure 1 is an end elevation of the improved display rack, constructed in accordance with my invention.

50 Figure 2 is a vertical transverse sectional view.

Figure 3 is a horizontal sectional view, Figure 4 is a detail perspective view of one of the supporting arms, illustrating the relative position of the stop arm with respect thereto, and

55 Figure 5 is a detail vertical section taken through one of the stop arms, illustrating the manner of connecting the same to the supporting bar.

60 Referring now more particularly to the drawings, in which reference characters are used to designate the several parts throughout, the numeral 1 indicates the end portions of the rack which in the present instance are 70 U-shaped, having their intermediate portions arcuate, as shown at 2 and the ends thereof are bent outwardly to provide the supporting feet 3.

65 In order to support the end members 1 in an upright position, the U-shaped supporting shelves 4 are provided, the arms 5 of which are bolted or otherwise detachably connected to the side portions of the end members 1 as indicated at 6, wherein it will 80 be apparent that these supporting shelves 4 may be quickly and readily connected with the end portion or disconnected therefrom. In order to provide for a substantially rigid connection between the two end members, 85 the brace bars 7 are used, the ends of which are turned outwardly as at 8, and bolted or otherwise connected with one shank portion of the end members 1 as indicated at 9.

90 The side arms 5 of the supporting shelves 4 are retained against spreading movement by means of a cross rod 10, the ends of which are connected to the members 5 adjacent the inner ends as shown at 11, said cross rods also providing feet, to which the inner ends of the supporting bars 12 are connected. While the supporting shelves 4 may be arranged between the end members 1 in the inclined position illustrated in the drawings, the supporting bars 12 are also 100 arranged in an inclined position and the outer ends thereof are rigidly connected to the longitudinal portion of the supporting shelves 4.

105 In the construction of the rack, several of these supporting bars 12 are arranged in spaced relation between the side portions 5 of the supporting shelves and mounted thereon are the stop arms 13, said arms 13 being mounted for longitudinal adjustment 110 upon the bars 12. The stop arms 13 are preferably constructed from a single strip.

of material, bent intermediate its width to form the side walls 14 which define the channels 15, one end of which is bowed as at 16. The bottom wall 16 of the channel is bifurcated at one end to provide the spaced ears 18 arranged upon opposite sides of the supporting bar as illustrated in Figure 4, and in order to provide for the adjustment of the stop arm upon the supporting bar 12, the 10 bar is provided with a longitudinal slot 19 and arranged within this slot is a connecting pin 20 the ends of which are fixed to the spaced ears 18, whereby the stop arms may be readily moved upon the supporting 15 bars, but the limit of movement being confined to the length of the slot 19.

The arms 13 when in an operative position are disposed at substantially right angles to the bar 12 as illustrated in Figure 4, 20 and substantially at an acute angle with respect to the end members 1 as shown in Figures 1 and 2. In order to prevent sliding movement of the arm 13 with respect to the bars 12, when the arms 13 are arranged in an operative position, and it will be noted that the inner wall of the slot or 25 recess 17 binds against the upper longitudinal edge of the bar and retains the arm 13 in its operative position. Attention is called 30 to Figure 5, wherein one of the arms is shown in an operative position and adjusted the limit of its movement toward the outer end of the bar 12 showing the manner in which the inner wall of the slot 17 binds 35 against the upper longitudinal edge of the bar 12 to prevent movement on the part of the arms 13 with respect to the bar.

As stated heretobefore, it is the principal 40 object of my invention to provide a rack being particularly adapted for use in the displaying of caddies which are used for shipping tea and other articles of merchandise of this character. These caddies are generally made up of three separable sections, known as a one-third caddy, a two-third caddy, and a whole caddy, and in the 45 construction of my improved display rack, I provide for the supporting and displaying of the several sections of the caddy, so that when the display rack is viewed from the front it presents a uniform appearance.

When it is desired to display the whole 50 caddies upon the rack, the use of the arm 13 is eliminated, said arm being folded 55 downwardly onto the bar 12, the only portion of the arm remaining to be exposed above the longitudinal edge of the bar being the wall portion 16. The wall portion 60 16 being of comparatively thin material, it will not interfere with the correct positioning of the caddy upon the supporting 65 bars 12, the arrangement of the whole caddy within the device being illustrated in the lower portion of Figure 1. In order to support a two-third caddy upon the rack, so

that its outer end will be disposed in alignment with the outer end of the whole caddy, the arms 13 are adjusted upon the bar 12, until the pin 20 reaches the inner end of the slot 19 formed in each of the bars 12 as 70 shown in Figure 2, the arms 13 forming a stop adapted to engage the inner ends of the two-third caddy to retain the same in proper position. In order to support a one-third caddy upon the rack, so that the outer end thereof is disposed in alignment with the remaining articles upon the rack, the arms 13 are adjusted forwardly upon the bars 12 until the pins 20 reach the outer end 75 of the slot, the arms 13 when in this position forming a suitable stop adapted to engage the inner ends of the one-third caddy to retain them in proper position. It will be apparent that a sufficient number of the various sections of the caddy will be arranged longitudinally of the rack to present the uniform appearance both vertically and longitudinally of the rack. 80

While I have illustrated the rack as particularly used for the display of various sized caddies, it will be apparent that articles of merchandise of various sizes and shapes may be disposed upon this rack by adjusting the stop arms 13 within the confines of the slot 19 of the supporting bar, as 90 the arms 13 will be retained in an upright position in various adjusted positions by having the inner wall of the recessed portions binding or contacting the upper longitudinal edge of the supporting bars 12. 100 Attention is called to the fact that when displaying the whole caddy or articles of merchandise which require the whole width of the display rack, the brace members 7 form suitable stops adapted to engage the 105 rear ends of the articles to retain them against sliding movement upon the brace rods 10 or supporting bars 12 so that the forward ends of the articles will be retained in substantial alignment when arranged 110 within the rack. 110

It will be noted that these shelves 4 may be arranged in different inclined planes, and in order to provide for this arrangement, the side portions of the end members 1 are provided with a plurality of spaced bolt openings 21 to accommodate the bolts which secure the shelves to the end portions. Attention is called to the fact that the supporting bars 12 are rigidly connected to the cross rods 10 and the intermediate portions of the shelves 4 by riveting or welding as desired. 115

In view of the fact that the main parts comprising my improved display rack are detachably connected by means of bolts or similar fastening members it will be apparent that the rack may be quickly and easily assembled or disassembled, and when disassembled occupy a minimum space for stor- 120 125 130

ing or shipping, in view of the fact that the main parts of the rack which comprise the supporting shelves 4, the brace rods 7 and the end parts 1, may, when disassembled, be arranged in compact form.

While I have shown and described the preferred form of my invention, it will be apparent that various changes and alterations may be carried out without departing 10 from the spirit of the invention or the scope of the appended claims, in which—

I claim:

1. A rack comprising upright end sections, supporting shelves arranged between and 15 connected to said end sections, transverse bars carried by said shelves each having a longitudinal slot, stop arms mounted for adjustment upon the transverse bars, and a pin carried by each of the stop arms movable 20 within the slots to slidably and pivotally mount the stop arms, the stop arms being provided with means other than the pins for limiting swinging movement of the arms and causing frictional binding to prevent 25 accidental sliding of the arms out of a set position.

2. A display rack including supporting bars having longitudinally extending slots, stop arms, and pins passing through said 30 slots and engaging said arms to pivotally and slidably connect the arms with said bars, said arms having abutments for engaging said bars and limiting swinging movement of the arms and through engagement 35 with the bars causing frictional bind-

ing to prevent sliding of the arms upon the bars out of set positions thereon.

3. A display rack including supporting bars having longitudinally extending pin seats, stop arms formed of channel strips 40 and adapted to straddle the bars when extending longitudinally of the bars in an inoperative position, the side leaves of said arms being provided with hinge ears at one end, and pins engaging said ears and fitting into said pin seats to pivotally and slidably mount the arms whereby the arms may be swung upwardly to an operative position at right angles to said bars and be held in set positions longitudinally of the 45 bars by frictional engagement with the bars.

4. A display rack including supporting bars having longitudinally extending slots, stop arms carried by said bars and formed of channel strips U-shaped in cross section and 50 having their side leaves extended at their lower ends to provide spaced hinge ears extending upon opposite sides of said bars, and pins extending through said slots and engaging said ears to pivotally and slidably 55 mount said arms, said arms when swung upwardly to an operative position at substantially right angles to the supporting bars having engagement with the upper edges thereof and causing frictional binding 60 between the pins and upper edges of the slots to prevent sliding of the arms out of 65 set positions.

FRANK E. BOGA.
